FLUID DISPENSING DEVICE

John C. Griesemer, Reading, Pa.

Application May 26, 1938, Serial No. 210,264

6 Claims. (Cl. 221—84)

My invention relates to fluid dispensing devices, such as gasoline pump nozzle portions, and to elements thereof adapted to other purposes.

In dispensing gasoline, as from wayside stations to automobiles, electrostatic sparks have occurred upon placing the pump hose nozzles into the intake tubes of the receiving tanks, resulting in disastrous explosions and fires, with the consequent injury to, or loss of life of, the attendants, and damage to property.

Static charges of electricity are generated by the flow of gas through tubes or nozzles of certain materials, such as those of rubber, or having rubber linings, such that, when the tubes or nozzles are approached to the tanks, the charges are discharged as sparks, to ignite the gas or vapor, which is extremely volatile, and easily ignitable in the vicinity of the intake tubes.

Also, and especially in modern automobile construction, these intake tubes have become longer and more irregular in shape, whereby they are provided with hard, or sharply bent, elbows or turns along their length from the points of entry to the tanks to the points of admitting the gasoline; this feature resulting in inability to properly place the nozzles in the tank openings, preventing the escape of air, spilling the gas, and having other disadvantages.

Gasoline pump nozzles are of different sizes, even at the same station, and are supported, when not in use, by holders or hostlers, such that a hostler adapted to a nozzle of one length may not be adapted to a nozzle of another length.

The nozzles are subject to hard usage, such as dropping, usually on concrete, or other hard surface, coming into contact with the metallic pump bodies, and other abuses, such that they are frequently damaged.

Tubular structures adapted to the above-mentioned, and other purposes, in which lateral flexibility, and longitudinal extensibility, are required or desired, are not known to me, so that, in the production of my invention, this is a feature which is requisite thereto in certain of its aspects, and has other uses.

Thus, with all of the above-mentioned factors of danger from sparking, the difficulty of fitting the nozzles to modern intake tubes, the hard service, likelihood of damage to the nozzles, and other factors, the provision of a device to overcome all such disadvantages in this and other fields, presents a very particular problem, which to the best of my knowledge has never, prior to my invention, been solved in any one tubular structure, or so well in any of the separate factors.

Accordingly, it is one object of my invention to provide a tubular structure for dispensing gasoline, or fluids or liquids of like explosive, or readily inflammable character, that shall prevent, or reduce, the likelihood of damage from such cause.

Another object of the invention is to provide a fluid dispensing tube, or like device, of the above-indicated character, that shall be readily adapted to tank intake tubes of practically all shapes now employed.

Another object of my invention is to provide a tubular structure of the above, or like, character that shall be less subject to the damage indicated, and that shall lend itself to more ready repair, and salvaging of its parts than similar devices heretofore employed.

Another object of my invention is to provide a tubular structure that shall combine the above and other objects in any number and relation.

Another object of the invention is to utilize the parts of the device, in any of its characteristics herein disclosed, for equivalent or other purposes for which they are adapted.

A further object of the invention is to provide a device of the above-indicated character that shall be simple and durable in construction, economical to manufacture, and effective in its operation.

With such objects in view, as well as other advantages which may be incident to a utilization of the improvement, the invention comprises the elements and combinations thereof hereinafter set forth and claimed, with the understanding that the several necessary elements constituting the same may be varied in proportion, arrangement, texture, and other features, without departing from the spirit and scope of the invention as intended, and as set forth in the drawings, specification and claims.

In order to render the invention more clearly understood, means are shown in the accompanying drawings for carrying the same into practical effect, without limiting the improvements in the useful applications thereof to the particular constructions shown and described, which are given merely by way of example.

In the drawings:

Figure 1 is a view, in side elevation, of a tubular structure constructed in accordance with one form of the invention;

Fig. 2 is a view, in vertical central plane section, taken substantially along the line 2—2 of Fig. 1;

Fig. 3 is an enlarged longitudinal detail sectional view, in longitudinally extended form, of

an outer sheath member, as viewed in Fig. 2, and taken along the line 3-3 of Fig. 1;

Fig. 4 is a view, similar to Fig. 3, of the structure thereof in longitudinally contracted form;

Fig. 5 is a side elevation of the device, as it appears in service connected to a hand valve; and

Fig. 6 is a perspective view, showing an automobile gasoline tank, and an intake tube in section, in which a nozzle of the invention is disposed.

Referring to Figs. 1 and 2, a unit proper, or the parts thereof severally and in various combinations, comprises a tubular adapter element 10, as of brass, having an externally screw threaded end section 12, adapting the element for attachment to a conduit or hose supply line, or equivalent structure, such as a gasoline service valve 17 and a hose 18 (Fig. 5). An opposite end 19 of the adapter has a serrated, or otherwise treated or prepared outer surface, for telescopically receiving thereover a flexible tube 22 of non-sparking material, such as Neoprene, synthetic rubber, Throkol, or any other material that is flexible, and adapted for the use of handling gasoline, other motor fuels, petroleum products, and any of various other gaseous or liquid fluids.

Means, such as a thin metal ferrule 23, as of brass, may be held tightly to the inner tube 22 telescopically thereover, to press the yieldable walls of the tube 22 against the serrated end 19, or the parts, including the adapter 10, the inner tube 22 and the ferrule 23 may be otherwise attached to each other, as by crimping the ferrule to the inner tube, and soldering the ferrule to the adapter.

A longitudinally extensible, laterally flexible metallic tubular structure, or outer sheath 27 for the inner tube 22, is constructed of thin metal stripping, as of brass, bronze, or other metal, or composition of non or low electrostatic spark characteristics for its service as a gasoline dispensing tube, or of further material dependent upon the particular use to which it is put, or other reason.

In its service as a gasoline dispenser, as shown, the sheath 27 is of sufficiently larger interior diameter than the outer diameter of the inner tube 22 to allow free longitudinal relative movement between the sheath and the tube, as will appear, and not to interfere with free lateral flexing of the composite structure; the sheath being secured, at one end, to the adapter 10, as by soldering, and extending, in its elongated or extended state, to a position beyond the other, or mouth, end of the inner tube 22. At the corresponding end of the sheath 27, the latter is provided with a non-arching ferrule, or tip element, 28, as of brass or other material mentioned, which telescopically fits over the sheath, secured thereto, as by soldering, and has a reinforcing inturned outer end flange 29.

As shown more clearly in Figs. 3 and 4, the strip from which the sheath 27 is constructed, is of substantially S-section having relatively long straight portions 32 and 33 of small and large diameters, respectively. The small diameter portion 32 has an outwardly turned flange 37, and the large diameter portion 33 has an inwardly turned flange 38, so that, when the strip is helically wound, to form the tubular structure, or sheath, the flange portions 38 overlap the flange portions 37. This arrangement, in addition to rendering the structure laterally flexible, renders it longitudinally extensible, as from its contract-

ed condition of Fig. 4 to its extended condition of Figs. 1, 2 and 3.

Thus, when operating as a gasoline pump nozzle element, the structure adapts itself to hostlers, whether of exact fit or not, or, in other words, two or more such nozzle elements of different actual lengths may fit hostlers of the same size, and the extensible feature has other advantages in other fields, such as not requiring to be cut to exact length when being installed as a conduit for any purpose.

As shown in Fig. 5, the composite tubular structure having the component parts above set forth, is secured to the hose 18, through the valve 17, which further comprises a valve plunger, or operating rod 42, an actuating handle 43, and a guard 45.

Fig. 6 illustrates the adaptability of the device of the other figures to an intake tube 47 of an automobile gasoline tank 48. The tube 47 is illustrative of a tube of modern practice, having relatively acute, sharp or hard bends or elbows.

With the device of the invention operating as a gasoline pump nozzle, it may be inserted deeply into the tube 47, and, at the same time, allow the escape of air, without spilling the gas from back pressure, by reason of the grooved or corrugated outer surface contour of the nozzle; this feature being in marked contrast to stiff or tapered nozzles, which can only be placed short distances into the intake tubes, and cause spilling of the gas.

By reason of the non-static generating character to the inner tube 22, grounded to the adapter 10, and the fact that the gasoline touches the outer sheath 27 before being discharged, and by reason of the fact that each of the other parts is of low or non-arching character, the device is extremely free from danger from sparking, and provides a new factor of safety in devices of this character.

Being flexible, it is less subject to injury from bending stresses, facilitates its entry into tank intake tubes, stands abuses, such as dropping on hard surfaces, and adapts itself to hostlers of different sizes.

It is the first nozzle of its kind, of which I am aware, whereby, upon damage to any of its major component parts, these may be replaced, without replacing the entire unit, and it has many other advantages, such as providing for maximum delivery of gas, rendering it an improvement generally in the art to which it relates.

I claim as my invention:

1. A tubular structure for dispensing gasoline and the like, comprising a metallic outer sheath of helically wound strip material rendering it longitudinally extensible and laterally flexible, and non-sparking means in the sheath protecting the same against leakage laterally therethrough of liquid flowing through the structure.

2. A tubular structure for dispensing gasoline and the like, comprising an adapter, a flexible inner tube secured at one end to the adapter, and an outer metal tubular sheath helically wound to tubular form from strip material of substantially S-section having overlapping edges longitudinally interlocking each other and rendering the sheath laterally flexible and longitudinally extensible.

3. A tubular structure comprising an adapter, a flexible inner tube secured at one end to said adapter, and an outer metal tubular sheath helically wound to tubular form from strip material of substantially S-section having overlapping

edges interlocking each other longitudinally of the structure and rendering the sheath laterally flexible and longitudinally extensible.

4. A tubular structure for dispensing gasoline and the like, comprising a flexible inner tube, and an outer metal sheath helically wound to tubular form from strip material of substantially S-section having overlapping edges interlocking each other longitudinally of the structure and rendering the sheath laterally flexible and longitudinally extensible.

5. A tubular structure comprising a flexible inner tube, and an outer metal sheath helically wound to tubular form from strip material of

substantially S-section having overlapping edges interlocking each other longitudinally of the structure and rendering the sheath laterally flexible and longitudinally extensible.

6. A tubular structure for dispensing gasoline and the like, comprising an adapter, a flexible inner tube having non-static characteristics and secured at one end to the adapter, and an outer metal tubular sheath helically wound to tubular form from strip material of substantially S-section having overlapping edges longitudinally interlocking each other and rendering the sheath laterally flexible.

JOHN C. GRIESMER.
